FURNACE FOR HEAT TREATING WIRE

Charles D. Johnson, Worcester, Mass., assignor
to Johnson Steel and Wire Company, Inc.,
Worcester, Mass., a corporation of Massachusetts

Application September 23, 1941, Serial No. 411,979

1 Claim. (Cl. 266—3)

This invention relates to furnace for heat treating wire and particularly to a novel means for sealing the delivery end of the furnace so as to prevent the heated wire which is delivered from the furnace from contact with air until after the wire has cooled to a point where contact with the air will not produce any deleterious oxidizing effect.

In order to give an understanding of the invention, I have illustrated a selected embodiment thereof in the drawing which will now be described after which the novel features will be pointed out in the claim.

Fig. 1 is a view partly in section illustrating a furnace for heat treating wire embodying my invention.

Fig. 2 is a section on line 2—2 Fig. 1.

In the drawing, 1 indicates a furnace of any suitable type by which the wire 2 is subjected to the heat treatment, the furnace being of that known type which is provided with a plurality of tubes 3 which extend through the furnace from one end to the other thereof and through which the wire, 2 to be heat treated is passed. The furnace may be equipped with any number of these tubes 3. The tubes 3 are filled with a non-oxidizing gas so that during the heating of the wire it is in a non-oxidizing atmosphere. For this purpose each tube 3 has an inlet pipe 4 connected thereto through which the non-oxidizing gas is delivered to the tube. The delivery end 5 of each tube communicates with a chamber 6 which during the operation of the furnace is filled with a non-oxidizing gas which is introduced thereto through the tubes 3. This chamber 6 is shown as having a discharge pipe 7 rising therefrom which provides an escape for the gas in the chamber 6.

In the operation of the furnace, a supply of gas is continually being delivered to each tube 3 through its supply pipe 4 and a certain portion of this gas will escape from the entering end 8 of the tube 3, while the remainder of the gas flows through the tube 3 into the chamber 6 and escapes through the discharge pipe 7. The gas escaping from the inlet end 8 of each pipe is ignited to produce a flame 9, and similarly any gas escaping from the discharge pipe 7 is ignited to produce a flame 10.

Associated with the chamber 6 is an oil-containing pan 11 which contains a body of oil 12. The dividing wall 13 between the chamber 6 and the oil pan is provided with apertures 14 situated in alignment with the various tubes 3, said apertures being below the level of the

oil in said pan. The wire 2 which is delivered from each tube 3 passes through the chamber 6 and then through the corresponding aperture 14 into the body of oil 12 in the oil pan 11.

Since each tube 3 and the upper portion of the chamber 6 is filled with the non-oxidizing gas and since the oil level in the pan 11 is above the apertures 14, each strand of wire is sealed against contact with the air until it is withdrawn from the oil bath 12. By the time the wire emerges from the oil bath it has been sufficiently cooled so that it will not become oxidized by contact with the air.

The oil level in the pan 11 is maintained at a point above the apertures 14 thereby preventing any air from entering the chamber 6. There will, therefore, be a constant flow of oil through each aperture 14 into the chamber 6 as shown at 15, but means are provided for maintaining the proper oil level in the pan 11 at a point above the apertures 14.

Each end wall of the chamber 6 is formed in two sections, a lower section 28 and an upper section 25. These two sections of each end wall are offset from each other, each lower section 28 being on the outside of the corresponding upper section 25. The upper edge 29 of each lower wall section 28 is situated below the tubes 3, and the lower edge 30 of each upper wall section 25 extends below the upper edge 29 of each lower wall section 28.

The oil which flows through the aperture 14 will accumulate in the chamber 6 as shown at 26 to a level determined by the upper edge 29 of the lower wall sections 28. When the body of oil in the chamber 6 is at this level as shown in Fig. 2, the lower edges 30 of the upper wall sections will be submerged in the oil and the space 18 between the upper edge portion of each wall section and the lower edge portion of the corresponding upper wall section will constitute a spillway through which the surplus oil is discharged from the chamber 6, as shown at 20, into a collecting pan or vat 19. 21 indicates a suitable pump having its inlet 22 submerged in the oil 23 which collects in the tank 19 and having its outlet 24 extending through the bottom of the oil pan 11. This pump serves to pump oil from the tank 19 into the pan 11 thereby maintaining the proper oil level in said pan. Since the lower edges 30 of the upper wall sections are submerged in the bath 26 of oil, the non-oxidizing gas which flows into the upper portion of the chamber 6 between the upper wall sections 25 becomes trapped therein

and can only escape through the outlet pipe 7. These upper wall sections 28 thus cooperate with the oil bath to form a seal which prevents air from entering the chamber 6 through the spillway 18.

In the operation of the device, the wire to be treated is delivered to each tube 3 through its entering end 8 and as the wire passes through the heated tube 3 it receives its heat treatment in a non-oxidizing atmosphere. As the wire emerges from each tube 3, it passes through the upper portion of the chamber 6, which is also filled with non-oxidizing gas, and thence it passes through the opening 14 into the oil bath 12 which serves as a cooling bath thereby to cool the wire to a point where it will not be oxidized by contact with the air. Inasmuch as the oil level in the pan is maintained above the apertures 14, said oil serves to seal the apertures against the admission of air and hence each wire can have no contact with the air until it has been delivered from the oil bath 12.

I claim:

A furnace for heat treating wire comprising a furnace element having a tube extending therethrough through which the wire to be treated is passed, a sealing chamber with which the delivery end of the tube communicates, one side wall of said chamber being made with an upper

section and a lower section which are offset with respect to each other, said lower section being situated outside of the upper section and the top edge of the lower section being located 5 below the delivery end of said tube but above the lower edge of the upper section, an oil-containing pan, one end wall of which is formed by the side wall of the chamber opposite to that through which said tube enters, said combined chamber side wall and pan end wall having an aperture in line with said tube and through which the wire passes, means to maintain the oil in the oil pan at a level above said aperture, whereby the oil draining into said chamber through said aperture maintains an oil level in the chamber which is determined by the upper edge of the lower wall section and is above the lower edge of the upper wall section, the lower edge of the upper wall section being submerged 10 in the oil in the chamber, the space between the lower wall section and the upper wall section constituting a spillway for oil accumulating in said chamber, and means to maintain the tube and the portion of the chamber above the oil level therein filled with non-oxidizing gas, said submerged edge of the upper wall section in co-operation with the oil forming a seal for said chamber.

CHARLES D. JOHNSON.
